METHOD OF MANUFACTURE OF MATRICES
AND CASTING BEDS

Theodore C. Browne, Winchester, Mass., assignor
to Dewey and Almy Chemical Company, North
Cambridge, Mass., a corporation of Massachu-
sets

Application April 25, 1946, Serial No. 664,931

6 Claims. (Cl. 18—55)

1

My present invention relates to a rapid and efficient method of making molds or casting beds.

Heretofore it has been proposed that molds or casting beds for orthopedic impressions, for instance, of feet for corrective lasts and anatomical patterns for the design of chair seats be made by taking the impression upon a bed of sand covered with a flexible diaphragm such as a rubber sheet. Then, after the impression is made in the sand and while the sand is still under pressure from the pattern, exhausting the air from beneath the diaphragm.

This procedure was based on the discovery that, if air is exhausted from the sand while the sand is under pressure from the pattern and consequently is in close-packed condition, it will retain close-packing and permit the whole body of sand to act as a massive solid as long as the vacuum is maintained. On the release of the vacuum, however, close-packing is no longer maintained, and the whole mass reverts from a solid system to a mobile system. This phenomenon is ordinarily referred to as "dilatancy."

Such a procedure has been used effectively to produce molds or casting beds having rounded or gentle contours. But when the contours are sharp or when there are substantial projections, as in the case of type or other sharply outlined patterns, I have found that sharp definition, if it is initially produced at all, is not maintained.

There may be several reasons for this. First, the diaphragm fails to follow the contours in the sharp indentations of the pattern. Instead, it bridges between the projections. Second, when the vacuum is drawn, the diaphragm tends to pull against what should be the sharp corners of the sand and tends to round them off. Third, the diaphragm becomes pinched between the projections of the pattern and the sand immediately beneath so that some parts of the diaphragm are tightly stretched and do not follow the outline of the relief.

When gentle contours are reproduced, these difficulties do not appear, and the mold or matrix which is produced by using the dilatancy principle has considerable stability. But perhaps the most serious difficulty, which prevents the use of such a molding bed in pressure molding operations, is the lack of lateral strength or the stability of what may be termed the columns of sand. This possibly occurs because, as the pattern is forced against the diaphragm and down into the sand, the maximum pressure and hence the maximum packing concentrates directly beneath the projections of the pattern while the pressure in

2

the low areas (for example, the shoulder areas of type) is low or non-existent. In any event, a molding compound forced laterally against a vertical matrix wall meets small resistance, and the walls collapse.

My invention is based on the discovery that, if the pressure applied to the sand is uniform over the whole area independently of whether or not a projection or a depression is involved, true close-packing is produced throughout the whole sand mass and the strength of the mold is thereby greatly increased, particularly in shear, so that the walls of the projections have stability enough to withstand the lateral flow of a molding composition, and that such uniform pressure may be obtained by first bringing the diaphragm into full enveloping contact with the pattern, allowing the sand to fill and form a negative pattern contour on the opposite side of the diaphragm and then placing the whole bed of sand under compression. Since the whole bed of sand is under uniform compression the distribution of pressure approaches the hydraulic ideal. Lateral compaction as well as column pressure is secured.

My new method also produces the maximum definition in the mold. Because the diaphragm is moved into full enveloping contact with the pattern and is maintained in such contact before any pressure whatever is applied to the sand, I have found that the process is suitable for the reproduction of patterns of many descriptions, molded parts, costume decorations, buckles etc., but for convenience and brevity in description and illustration, I describe the process as applied to the reproduction of type.

The invention may be better understood by reference to the drawings in which

Figure 1 is a longitudinal cross-section through the matrix or sand box;

Figure 2 is a longitudinal cross-section through the pattern or type box;

Figure 3 is a longitudinal cross-section view of the two parts superposed on a press ram before the formation of the matrix;

Figure 4 is the same longitudinal cross-section view after compression; and

Figure 5 is a fragmentary cross-section of the completed matrix ready for subsequent molding operations.

Figure 6 illustrates a variant of the process shown in Figures 2 and 3, wherein the relative positions of pattern chamber and sand bed have been reversed.

The apparatus comprises a matrix or sand box

10. To permit the uniform withdrawal of air,

the box 10 has a step 11 formed in its walls 12 upon which is fastened a stiff perforated metal plate 13. Studs 23 stiffen and support the plate. A layer of stiff screening 14 is fitted over the plate 13 and upon this is placed a filter pad 15; depending upon the size of the sand grain, this may be felt, paper, or a ceramic or sintered metal filter plate. The filter 15 is sealed to the side wall 12 by a holding fillet 16.

The top surface of the wall 12 terminates in a soft rubber gasket 17, the purpose of which is to prevent cutting and tearing of the thin rubber diaphragm 18 which is stretched over the sand S and held in place by a cord or spring seizing 19 fitting into the groove 20 cut in the outside of the wall 12. A flexible hose 21 connects the port 22 in the sand chamber with a vacuum pump (not shown).

The pattern or type chamber consists of a shallow box 30 having walls 31 topped by a stiff perforated plate 32, which is also supported by the studs 37. To prevent the type from shutting off the flow of air, the top surface of the plate 32 is knurled, or it may be covered with a fine mesh wire screen. An angle iron frame 33 is attached to the plate 32 to provide an abutment for the quoins or to center the chase as the case may be. (For simplicity of illustration the quoins and furniture are indicated by the cross sectioned blocks Q. A chase has not been shown.) A sponge rubber gasket 34 is mounted around the margin. A flexible hose 35 connects the port 36 in the box 30 with a vacuum pump (not shown).

The type is mounted in the type box in any suitable manner (usually the whole chase is laid in the box). The furniture and quoins are covered with felt, indicated at F in Figure 3, to prevent cutting and injury to the diaphragm, but to allow proper seating, a free space over the quoins and furniture is left to receive the displaced sand. The volume of the free space should equal the volume of the plate one intends to produce.

In operation, the pattern or type box 30 containing the type T, is placed on the ram 40 of a press. The sand box 10 is then placed on top of the type box 30 with its diaphragm 18 engaging the gasket 34 of the type box as shown in Figure 3. Bearers 41 are placed between the press platens so adjusted that by compression of the sponge rubber gasket the proper plate thickness will be produced. For example, to produce a plate of 0.183 inch thickness, a bearer height is chosen which will project the face of the type 0.183 inch into the sand box when the press is fully closed.

Then the press is closed with just enough pressure to compress the sponge rubber gasket slightly and make an air-tight seal between the parts 10 and 30. Air is now exhausted from the type box while the port 22 leading into the sand chamber is fully open to the atmosphere. This operation forces the diaphragm into complete contact with the type, and since the diaphragm is stretchable as well as flexible, it molds itself about the minute details of the type, for example, the serifs. Alternatively, air pressure applied to the sand while the pattern box 30 remains at a lower pressure will produce the same result. The sand falls into place. Its proper and uniform rearrangement may be assured by vibrating the sand box with a foundry flash vibrator. Then the press is closed to the bearers, the compression being taken up by the sponge gasket 34. This puts a uniform pressure on the whole sand mass. The diaphragm is not moved

or stretched during the compression, and the columns of sand whether rising from the face of the type or from the type shoulder are under equal pressure.

After the press is seated, air is exhausted from the sand box through the pipe 21, and thereafter air is admitted to the type box through the port 36. Then the press is opened and the parts 10 and 30 separated.

As long as the sand box 10 remains under reduced pressure with respect to the external pressure on its diaphragm, the matrix which the previous operations have formed has considerable rigidity and may be used for casting, electroplating, or for low pressure molding by procedures which are otherwise conventional and are, therefore, not further described.

A valuable property of the matrix so formed is its self-destructibility. When the molding or casting operation is complete, the vacuum is turned off and air is admitted through the port 22. The matrix immediately becomes mobile and releases itself from the finest details of the cast or molded materials.

As a variant in the process, the diaphragm may be made of a heat softenable sheet material such as, for example, rubber hydrochloride, poly vinylidene chloride and polyethylene, and the diaphragm uniformly heated before the vacuum is drawn in the pattern box. Extremely delicate castings may be made, for the softened, plastic diaphragm molds itself about the pattern without tension and follows the pattern with microscopic fidelity.

The method of carrying out this variation of the process is illustrated in Figure 6. Some press constructions make it more convenient to reverse the relative positions of the pattern chamber and the sand bed with respect to the press. Whether this is desirable or not is dictated by the particular press. The drawing illustrates the pattern chamber attached to the upper bolster 42 of a hydraulic press 43. The sand chamber is shown placed on the press ram 40. The diaphragm 18a, in this case made of one of the heat-softenable materials as above described, is heated to a flowable, plastic state prior to forcing the diaphragm into contact with the pattern. Preferably this is accomplished by focusing radiant energy derived from a bank of infrared lamps on the surface of the diaphragm. This is preferred because of the ease of adjustment and the uniform radiation pattern which may be secured on the diaphragm. As a further alternate, hot air may be blown against the diaphragm, but is not so convenient because it is harder to obtain a uniform heat distribution. When the diaphragm has been brought to the proper temperature, the press is closed, the air is exhausted from the pattern chamber, and the process thereafter continues throughout as previously described. The elements of the sand bed and the pattern chamber being the same, the same reference numbers are used.

The definition which may be secured is determined by the maximum size of the sand grain and the thickness of the diaphragm if this be flexible and extensible. The finer the grain and the thinner the diaphragm, the greater is the definition. Twenty-four point type can be reproduced effectively with a diaphragm of chloroprene (unloaded save for vulcanizing ingredients) .0035 thick and sand grains passing 150 mesh.

The word "sand" has been chosen as a convenient generic word. I have used fine glass beads

as produced for motion picture screens, fly ash, Portland cement, and several types of sand, each successfully. Powdered metals as produced for powder metallurgy are very useful because of their superior rate of heat transfer. Flaked metals give inferior results. Diatomaceous earth produces a strong matrix, but has a tendency to felt and interlock after initial compression. Its matrix is not completely self-destructive. In short, the word means any loose, powdered material which may be given shape under pressure.

I claim:

1. The method of molding which includes the following steps: first bringing one side of an elastic diaphragm into intimate contact with a pattern and then bringing a bed of comminuted material having a fluid between the particles of said material on the other side of the diaphragm into intimate contact with the already shaped diaphragm, subjecting the comminuted material to pressure to cause it to assume a close-packed condition and maintaining said close-packed condition during molding by removing the fluid from the bed of comminuted material.

2. The method of molding which includes the following steps: first bringing one side of an elastic diaphragm into intimate contact with a pattern and then bringing a bed of comminuted material having a fluid between the particles of said material on the other side of the diaphragm into intimate contact with the already shaped diaphragm, subjecting the comminuted material to pressure operative laterally within said material as well as generally in the direction of the body of the pattern to cause it to assume a close-packed condition and maintaining said close-packed condition during molding by removing the fluid from the bed of comminuted material.

3. The method of molding which includes the following steps: softening a diaphragm of a heat softenable substance by heating it, bringing one side of said diaphragm into intimate contact with a pattern and then bringing a bed of comminuted material having a fluid between the particles of said material on the other side of the diaphragm into intimate contact with the already shaped diaphragm, subjecting the comminuted material to pressure to cause it to assume a close-packed condition and maintaining said close-packed condition during molding by removing the fluid from the bed of comminuted material.

4. In matrix forming apparatus, a sand-bed having a flexible gas-excluding diaphragm, means to remove a gas from the sand-bed, a pattern chamber having compressible walls, means for

removing air within the pattern chamber to cause said sand-bed diaphragm to advance into full contact with a pattern contained in said chamber, and means to cause the pattern chamber walls to compress and compact the sand-bed upon the pattern.

5. The method of molding which includes the following steps: first bringing one side of an elastic diaphragm into intimate contact with a pattern and then bringing a bed of sand having a fluid between the particles thereof on the other side of the diaphragm into intimate contact with the already shaped diaphragm, subjecting the sand to pressure to cause it to assume a close-packed condition and maintaining said close-packed condition during molding by removing the fluid from the bed of sand.

6. The method of molding which includes the following steps: first bringing one side of an elastic diaphragm into intimate contact with a pattern, removing air from the space between the diaphragm and the pattern, bringing a bed of comminuted material having a fluid between the particles of said material on the other side of the diaphragm into intimate contact with the already shaped diaphragm, maintaining the air pressure on the pattern side of the diaphragm below the pressure on the opposite side thereof, subjecting the comminuted material to pressure to cause it to assume a close-packed condition and maintaining said close-packed condition during molding by removing the fluid from the bed of comminuted material.
